UNITED STATES PATENT OFFICE.

BENJAMIN P. YOUMANS, OF VANCOUVER, WASHINGTON.

LOCK FOR TWO RELATIVELY MOVABLE LEVERS.

1,140,431.

Specification of Letters Patent.

Patented May 25, 1915.

Application filed May 26, 1914. Serial No. 841,046.

To all whom it may concern:

Be it known that I, BENJAMIN P. YOUMANS, a citizen of the United States, residing at Vancouver, in the county of Clarke 5 and State of Washington, have invented certain new and useful Improvements in Locks for Two Relatively Movable Levers, of which the following is a specification.

My invention relates to locking means for 10 rendering two relatively movable levers inoperative.

My invention further particularly relates to motor vehicles and in this connection has for its object the providing of simple means 15 for locking the reverse lever and the clutch lever in neutral position, so as to render the car unserviceable.

Other advantages of my invention will be made more clearly apparent in the following specification taken in connection with the accompanying drawing which forms 20 part of this application.

The figure shown is a perspective of a 25 part of a motor vehicle showing my invention attached thereto.

The steering column 2 is provided at its lower end with a peripheral flange 3, the latter being rigidly bolted to the foot-board of the machine by the bolts 4. The clutch- 30 member or lever is represented by 14, and the reverse member or lever by 9. The parts thus far described are all of well-known construction and need no further explanation.

An eye-bolt 5 is substituted for one of the 35 bolts 4. An arm 6 has one end pivoted to the said eye-bolt 5, and is free to be moved universally with respect to same. The arm 6 is made with a medial transverse, or off-set portion 8, and is provided with lock-means 40 13, including a shackle 12. The portion 7 of the arm 6 is made with a projecting portion 10, providing a shoulder.

My device is used as follows: When not 45 in use, the arm 6 is placed to one side out of the way, as indicated by broken lines in the figure. When it is desired to lock the

machine, the clutch lever 14 will be automatically placed in "neutral" position by the operation of the emergency brake, the latter not being shown in the drawing. The 50 reverse lever 9 is normally in "neutral". The arm 6 is then swung into the position in which it is shown in the figure, thereby placing the transverse portion 8 of the arm across the path of motion of the clutch lever 55 14, at the same time placing the shouldered portion 10 of the arm in engagement with the reverse lever 9. The shackle 12 of the lock 13 is then placed around the lever 14 and locked in place. The two levers 12 and 60 14 will then be locked in their "neutral" positions, rendering the vehicle inoperative.

I claim:

1. In combination with a fixed body, and two levers movable relatively thereto, and 65 an arm, pivoted to said fixed body, having means to engage and secure said levers in a certain relative position thereof; said means consisting of a shackle adapted for encircling one of said levers, lock means to secure 70 the shackle in such encircling position, and a shoulder located for engaging the other lever and obstructing the movement thereof.

2. In combination with a fixed body, and two levers movable relatively thereto, an 75 arm pivoted to said fixed body and formed with a medial offset portion located to obstruct the movement of one lever, a shackle hinged to said off-set portion of the arm for encircling said lever; lock means for securing 80 the shackle in its encircling position, and a shoulder on the arm located for engaging the other lever and obstructing the movement thereof.

In testimony whereof I hereunto affix my 85 signature in the presence of two subscribing witnesses.

BENJAMIN P. YOUMANS.

Witnesses:

MAUDE YOUMANS,
PETER HABERLIN.
